[57] CLAIM

The ornamental design for a slide hammer nail puller, as shown.

DESCRIPTION

FIG. 1 is a side elevational view of a slide hammer nail puller showing my new design;

FIG. 2 is a front elevational view thereof;

FIG. 3 is a horizontal sectional view taken downwardly along line 3—3 of FIG. 1;

FIG. 4 is a bottom plan view of FIG. 3; and

FIG. 5 is a top plan view thereof.
